UNITED STATES PATENT OFFICE.

OLE K. NELSON, OF CAPRON, ILLINOIS.

CABLE STOP FOR TRAVELING CARRIERS.

Application filed February 10, 1926. Serial No. 87,232.

This invention relates to a stop for traveling carriers of the type commonly used for transporting hay, ensilage, litter and other materials to or from a barn, and having 5 rollers to operate on a cable or a connected track and cable leading from within the barn to a convenient point for loading or unloading.

The stop of the present invention is designed to enable the positive holding of the carrier at any point along the length of its travel against drifting movement in either direction to avoid the annoyance and inconvenience commonly met with, due to a sagging of the cable.

The principal feature of the present invention is the provision of a stop for the purpose referred to, which may be applied to practically any type of carrier and is arranged to be suspended freely therefrom when not in use, and may be placed into position on either side of one of the supporting rollers of the carrier to have the roller roll upon and rest on the device along-side 25 an abutment provided thereon for holding the roller against movement.

The invention is more fully described hereinafter and is illustrated in the accompanying drawing in which—

Fig. 1 is a side view of a litter carrier or other similar traveling carrier operating on a cable and equipped with a cable stop in accordance with my invention;

Fig. 2 is a perspective view of the cable stop detached from the carrier, more clearly to disclose the form thereof; and

Fig. 3 is a fragmentary vertical sectional detail to illustrate the operation of the stop.

The same reference numerals are applied 40 to the parts in all three views.

The carrier 5 comprises the usual basket or bucket 6 and suspension frame 7 having brackets 8 extending therefrom and providing mountings for sheave rollers 9 to operate on a cable 10. The latter usually extends from a point within the barn or other enclosure from which or into which the material to be transported is to be taken and leads out to some other point remote 45 from the barn where the material is to be unloaded or loaded, as the case may be. Usually some form of trip device is provided at the remote end of the cable to unload the contents of the carrier when it arrives at its 50 destination where the carrier, for example, is used for transporting litter, trash or other

refuse from a barn. In some instances, a span of overhead track is provided within the barn and the cable is connected therewith in a manner permitting the riding of 60 the carrier from one onto the other. In many instances, however, the cable extends the entire length of the travel of the carrier.

Considerable inconvenience and annoyance has resulted in the operating of traveling 65 carriers of the type above described due to a sagging of the cable which resulted in the drifting movement of the carrier away from a position in which it was desired to keep the same as, for example, when loading. In 70 some instances, where litter to be loaded into the carrier is collected at different points in the barn and the carrier is brought from point to point, it used to be necessary either to hold the carrier in place or provide some 75 makeshift to prevent its movement during loading. According to the present invention, I provide a stop 11 which may be permanently attached, suitably to one of the brackets 8, by means of a chain or other 80 form of flexible connection to be placed on the cable 10 on either side of one of the rollers 9 to hold the carrier from movement in whichever direction it intends to drift. The permanent attachment of the stop to the 85 carrier in the manner shown insures against misplacing or losing the same and the stop is always handy for immediate application to the cable when the occasion arises. Sufficient slack is provided in the chain 12 to 90 enable placing the stop in either of the two positions in which the same is to be used.

As shown particularly in Figs. 2 and 3, the stop 11 comprises a U-shaped sheet metal strap bearing an integral lug or other suitable projection 13 to provide an abutment for the roller 9 when the roller rests on top of the stop with the stop straddling the cable 10 in the manner shown in Fig. 3. It will be seen that the stop is of small 95 enough proportions to be received in the peripheral groove of the sheave roller and permit the latter rolling over and upon the stop. The edge 14 of the stop is tapered, as indicated, to form an easy approach for the roller onto the stop in an obvious manner. If desired, the surface of the stop may be ground off in the vicinity of the projection 13, as shown at 15, to provide a hollow in which the roller 9 will ride when along-side of and in engagement with the projection 13. It is obvious that the projection 13

will be situated on that side of the roller toward which the carrier tends to drift. It is equally obvious that the stop can be placed with equal facility into position on either side of the roller. The stop serves as a frictional shoe and positively holds the carrier against drifting out of position. The weight of the carrier, it will be seen, is brought to bear upon the stop thus giving the latter a firm grip on the cable to avoid the likelihood of slipping.

It is believed that the foregoing gives a clear understanding of my invention and while I have illustrated but a single working embodiment it should be manifest that changes might be made in details of construction without departing from the spirit and scope of the invention as expressed in the appended claims, in which I claim:

20. 1. A cable stop for traveling carriers comprising a U-shaped strap member for straddling the cable with the two arms thereof depending on opposite sides of the cable,

said arms being of ample length and weight to act as counterweights to hold said strap member always in its proper position, and the bight portion thereof being narrow enough to fit within the peripheral groove of the pulley wheel of the carrier to permit the wheel to rest thereon, and a stop projection on the outside of said bight portion for engagement by said wheel.

2. A cable stop as recited in claim 1 arranged to be reversible end for end relative to said wheel to be used with said carrier traveling in either direction, and a flexible connection between said strap member and said carrier providing for the free suspension of said member on said carrier when not in use, said connection having sufficient slack therein to enable placing said member onto said cable on either side of said wheel.

In witness of the foregoing I affix my signature.

OLE K. NELSON.
